US00D981648S

(12) **United States Design Patent** (10) Patent No.: **US D981,648 S**
(45) Date of Patent: **** Mar. 21, 2023**

(54) **BASEBALL GLOVE**

(71) Applicants: **Takashi Yokoyama**, Gifu (JP); **Naoto Kamitake**, Osaka (JP)

(72) Inventors: **Takashi Yokoyama**, Gifu (JP); **Naoto Kamitake**, Osaka (JP)

(**) Term: **15 Years**

(21) Appl. No.: **35/513,873**

(22) Filed: **Jan. 26, 2022**

(80) **Hague Agreement Data**

Int. Filing Date: **Jan. 26, 2022**

Int. Reg. No.: **DM/218747**

Int. Reg. Date: **Jan. 26, 2022**

Int. Reg. Pub. Date: **Mar. 25, 2022**

Brian F. Bradley

(57) **CLAIM**

The ornamental design for a baseball glove, as shown and described.

DESCRIPTION

1. Baseball glove

1.1 : Perspective

1.2 : Front

1.3 : Back

1.4 : Left

1.5 : Right

1.6 : Top

1.7 : Bottom

The broken lines form no part of the claimed design; the dash-dot-dash lines indicate merely boundaries between the parts for which design registration is sought and the other parts.

1 Claim, 7 Drawing Sheets
